[57] CLAIM

The ornamental design for a vehicle tire, as shown and described.

DESCRIPTION

FIG. 1 is an end elevational view of a vehicle tire showing our new design, it being understood that the tread pattern is repeated throughout the circumference of the tire;

FIG. 2 is a side elevational view thereof, the opposite side being a mirror image thereof;

FIG. 3 is an end elevational view thereof, circumferentially offset from that of FIG. 1;

FIG. 4 is an end elevational view thereof, circumferentially offset from that of FIG. 3; and

FIG. 5 is an end elevational view thereof, circumferentially offset from that of FIG. 4.

FIG. 1

FIG. 2

FIG. 3

FIG. 4

FIG. 5
